Primary Examiner — Cathron Brooks*Assistant Examiner* — Christian P McLean*(74) Attorney, Agent, or Firm* — Norris McLaughlin & Marcus PA(57) **CLAIM**

The ornamental design for a bottle, as shown and described.

DESCRIPTION

FIG. 1 is a perspective view of a bottle, shown our new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines illustrate portions of the bottle that form no part of the claimed design.

1 Claim, 5 Drawing Sheets(56)
